(57) CLAIM

The ornamental design for a pen holder for binder clip, as shown and described.

DESCRIPTION

FIG. 1 is a perspective view of a pen holder for binder clip showing the claimed design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof; and,
FIG. 8 is another perspective view showing use state thereof. The broken lines in FIG. 8 are for the purpose of illustrating environment and form no part of the claimed design.
